Jack W. Soffer, St. Louis, Mo., assignor to Development Research, Inc., St. Louis, Mo., a corporation of Missouri

Application August 9, 1954, Serial No. 31,783

Term of patent 14 years

(Cl. D62—2)

FIG. 1

Figure 1 is a perspective view of a shaving lather dispenser or the like embodying my new design; and

The essential features of my design reside in the portions shown in full lines.

I claim:

The ornamental design for a shaving lather dispenser or the like, substantially as shown and described.
